CARL GEORG MUNTERS, OF STOCKHOLM, SWEDEN, ASSIGNOR TO ELECTROLUX SERVEL CORPORATION, OF NEW YORK, N. Y., A CORPORATION OF DELAWARE

REFRIGERATION

Application filed March 29, 1929, Serial No. 350,845, and in Germany May 25, 1928.

My invention relates to refrigerator cabinets or the like, the refrigerating apparatus of which contains a pressure equalizing inert gas circulating through the evaporator and 5 absorber of the apparatus.

One purpose of my invention is to provide such an arrangement of said refrigerating apparatus and especially of its evaporator and cooling bodies thereof that the characteristic temperature conditions prevailing in 10 the apparatus are in an effective way utilized for the production of cold.

According to the invention two cooling units or bodies, one provided for the purpose 15 of producing ice and the other one for cooling the air in the cabinet, are arranged on a common evaporator shell in such a manner that, when the apparatus is fitted in the cabinet, the cooling unit provided for the purpose 20 of producing ice is situated on the front end of said evaporator shell and facing the door of the cabinet, so that objects to be cooled, as, for instance, ice trays, arranged in said unit can be conveniently removed, 25 while the cooling unit provided for the purpose of cooling the air in the cabinet is situated behind said cooling unit for the ice production. In the following description, said two cooling units are referred to as the ice 30 producer and the air cooler respectively. The cooling units are so arranged on the evaporator shell that the evaporation of the refrigerant in the part of the evaporator taking up heat from the ice producer takes 35 place at a higher partial pressure drop than in the part taking up heat from the air cooler.

The invention will be more fully described with reference to the accompanying drawings 40 showing, by way of example, one embodiment of the invention and in which:—

Fig. 1 is a vertical section through a refrigerator cabinet with an absorption refrigerating apparatus mounted therein, arranged in accordance with the invention.

Fig. 2 is a front view of the ice producer, seen from the door opening of the cabinet and

Fig. 3 is a section along the line III—III 50 in Fig. 1.

Referring more particularly to Fig. 1, reference character 10 designates the refrigerator cabinet provided with a front door 11 within which an evaporator 12 is arranged so as to extend into the insulated cooling 55 chamber 13 from the rear wall 14 thereof. The evaporator 12 comprises a lengthened cylindrical vessel or shell, preferably of steel and arranged horizontally and parallel to a side wall of the refrigerator cabinet on 60 which are mounted the ice producer 15 and the air cooler 16. Liquid refrigerant to be evaporated in evaporator 12 is supplied through conduit 17 and is distributed in said evaporator over distributing plates 18, 19 65 and 20. The upper plate 18 and the upper wall of the evaporator form a horizontal channel closed at its rear end and open at its front end, said plate being provided, approximately at its center, with a transverse 70 rib 21 or the like and at its front end with another rib 22. Between these ribs 21 and 22 an overflow opening 23 is provided for the refrigerant. A raised rim is provided around opening 23. The refrigerant forms 75 a liquid pool on plate 18.

Reference character 24 designates the generator which contains the refrigerant or cooling agent, for instance ammonia, dissolved in a suitable absorption liquid, such as water. 80 Although it is obvious that various substances may be used as cooling agent, ammonia is preferred but, in describing the apparatus as using ammonia and specific related substances, it is to be understood that 85 this is by way of example only and without limitation. Ammonia vapor is expelled from the solution in the generator and passes through conduit 25, the upper part of which forms a rectifier 26, into condenser 27 which 90 consists of a water cooled coiled pipe, the end 17 of which enters evaporator 12 and opens into same in front of rib 21. The ammonia is condensed in the condenser, thus entering the evaporator in liquid state. The 95 liquid refrigerant consequently forms a liquid pool between ribs 21 and 22 and thereafter passes through opening 23 to the second distributing plate 19 arranged below the first one. Said plate 19 is provided at both 100

ends with ribs 28 and 29 respectively and an overflow 30 at its rear end, the remaining part of liquid refrigerant passing through said overflow to the third plate 20 which is 5 of a shape similar to that of the middle plate 19 except for the overflow in this case being arranged at the front end of the plate.

From absorber 31 an auxiliary medium, as for example hydrogen, is conducted 10 through gas heat exchanger 32 and conduit 33 and introduced in substantially pure state into evaporator 12 at its rear end, thence flowing through the upper channel, formed by plate 18 and the upper wall of 15 the evaporator, towards the front end of same. The liquid ammonia collected between ribs 21 and 22 evaporates rapidly in the hydrogen whereby a low temperature is obtained in the front end of the evaporator 20 and consequently in ice producer 15. The ice producer consists of a box-shaped metal cover arranged in a heat conducting relation to the front end of evaporator 12. In a preferred form, shown more clearly in Figs. 25 2 and 3, the ice producer consists of two parts 34 and 35, preferably of metal plates, clamped to the evaporator shell by screws or bolts 36 and provided at their free ends with inward bends so as to form special compartments 37 for receiving objects to be 30 quickly cooled down as, for instance, ice trays or containers. If it is desired to increase the rate of cooling, it is advisable to insulate the ice producer as indicated in Fig. 3 by 35 jacket 38 of heat insulating material, which preferably is unaffected by moisture. Further, a heat insulating filling 39, such as cork or the like, may be provided between said jacket 38 and the evaporator shell. Said insulating covers also can be made removable 40 so as to be applied only when an increased rate of ice production is desired. Further, the ice producer may be so constructed that the ice containers directly contact the evaporator body when inserted in the ice producer. 45

When the hydrogen has been saturated with ammonia vapor to a certain extent, that is, when the rate of evaporation of the liquid refrigerant collected on plate 18 has decreased, the gas mixture flows from the front end of evaporator 12 through channels 40, 41 and 42 formed by plates 18, 19 and 20, the side walls and the bottom wall of the evaporator to the rear end of same. The remaining part of liquid refrigerant collected 55 on plates 19, 20 and in the lower part of the evaporator thereby evaporates, thus producing cold at a higher temperature than in the first part of the evaporator. The enriched gas mixture leaves evaporator 12 and is led by gravity into heat exchanger 32 through conduit 43 and thence to absorber 31.

Due to the construction of the evaporator 60 above described, the evaporation of the re-

frigerant in the part corresponding to the ice producer, that is, in the front part of the evaporator, takes place at a higher partial pressure drop than in the rear part of same and thus a lower temperature is obtained in 70 the first mentioned part thereof.

As shown in the drawing, the air cooler 16, in this preferred embodiment of the invention, consists of metal flanges 44 arranged transversely on the rear portion of the cylindrical evaporator shell in a vertical or substantially vertical position permitting the air in the cabinet to circulate through the space formed between said flanges. 75

In the upper part of absorber 31, poor ammonia solution is introduced through conduit 45, part of which forms the outer conduit of a heat exchanger 46, the inner conduit 47 of which conducts rich solution from the lower part 48 of absorber 31 to chamber 49 forming an auxiliary generator. A flue 50 passes through chamber 49 and generator 24. A suitable source of heat, not shown in the drawing, as, for instance, an electric heating unit or resistance or a gas burner, is placed in the lower end of flue 50, which latter is arranged in a somewhat inclined position, whereby heat is transferred from said source of heat through the wall of flue 50 to chamber 49 and generator 24. Chamber 55 49 communicates with the upper part of generator 24 by means of conduit 51, the upper portion of which is made and arranged so as to form the upwardly extending vapor and liquid pipe of a thermo-siphon through 100 which ammonia solution is forced into generator 24 by means of ammonia gas expelled in chamber 49 and introduced into conduit 51 through gas conduit 52.

Having thus described my invention, what 105 I claim is:—

1. In a refrigerator, a cabinet, a horizontally disposed evaporator shell in said cabinet, air cooling means on the rear part of said shell, ice freezing means on the front part of said shell, means for introducing an inert gas into the rear part of said shell, a plurality of vertically spaced horizontally disposed liquid distributing plates within said shell, a transverse rib on the central part of the uppermost of said plates, a conduit for conveying liquid refrigerant to said shell, said conduit entering the rear part of said shell and extending forward of said transverse rib and means for removing refrigerant and inert gas from the 115 rear of said shell.

2. In a refrigerator, a cabinet, a horizontally disposed evaporator shell in said cabinet, air cooling means on the rear part of said shell, ice freezing means on the front part of said shell, means for introducing an inert gas into the rear part of said shell, a plurality of vertically spaced horizontally disposed liquid distributing plates within said shell, a transverse rib on the central part of the 120 125 130

uppermost of said plates, said uppermost plate contacting the interior of said shell along the rear and side edges of the plate and forming a passageway around the front of 5 said plate, the remaining plates contacting said shell along their side edges and forming passageways around both ends of the plates, a conduit for conveying liquid refrigerant to said shell, said conduit entering the rear part 10 of said shell and extending forward of said transverse rib and means for removing refrigerant and inert gas from the rear of said shell.

3. In a refrigerator, a cabinet having a 15 door and a rear wall, a horizontally disposed evaporator shell supported by said rear wall, air cooling means on the rear part of said shell, ice freezing means on the front part of said shell, a conduit extending through said 20 rear wall for introducing an inert gas into the rear part of said shell, a series of horizontally disposed plates within said shell, a transverse rib on the central part of the uppermost of said plates, a conduit for conveying 25 liquid refrigerant to said shell, said conduit extending within said inert gas conveying conduit and extending forward of said transverse rib and a conduit extending through said rear wall for conveying refrigerant and inert gas from said shell.

4. A refrigerating apparatus comprising a horizontally disposed evaporator shell, air 35 cooling means on the rear of said shell, ice freezing means on the front of said shell, means for introducing an inert gas into the rear of said shell, and a conduit for conveying liquid refrigerant into said shell, said conduit entering said shell at the rear and extending to the more forward part of the shell, said ice 40 freezing means comprising a pair of members each having an arcuate central portion in contact with said shell and U-shaped end portions forming rectangular compartments for the reception of ice trays and bolts passing through said members to clamp their arcuate portion around said shell.

In testimony whereof I have affixed my signature.

CARL GEORG MUNTERS.
